UNITED STATES PATENT OFFICE.

FRANK. P. MUSSER, OF BEAVER FALLS, PENNSYLVANIA.

THILL-COUPING.

SPECIFICATION forming part of Letters Patent No. 374,846, dated December 13, 1887.

Application filed September 17, 1887. Serial No. 249,939. (No model.)

To all whom it may concern:

Be it known that I, FRANK. P. MUSSER, of Beaver Falls, in the county of Beaver and State of Pennsylvania, have invented certain new and useful Improvements in Attachments for Thill-Couplings; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a thill-coupling, showing my improvement attached in operative position thereto. Fig. 2 is a longitudinal vertical sectional view of the same, and Fig. 3 is a perspective view of my invention removed from the thill-coupling.

Similar letters of reference denote corresponding parts in all the figures.

My invention has relation to attachments for thill-couplings for vehicles; and it has for its object to provide a device, as will be hereinafter fully described, that can be easily and conveniently attached to the ordinary coupling now in use to prevent rattling of the several parts of the same.

In the accompanying drawings, the letter A indicates the axle of a vehicle, to which an ordinary clip, B, having projecting perforated ears C, is secured. To these perforated ears is pivoted, by means of a bolt and nut, D and E, respectively, the thill-iron F.

A' denotes an L-shaped metallic piece having a T-head, M, and a screw-threaded aperture, N, in its base. A set-screw, O, projecting with its upper reduced and smooth end through this aperture, has swiveled to its said reduced end a socket-plate, P, formed with inclined ends Q and upwardly-projecting arms R at its sides. Seated in this plate and protected from lateral displacement by the upwardly-projecting arms is an elastic pad, S, having the forward and rear edges of its base beveled, as shown at T, to conform with the inclined ends of the socket-plate, while its top is concaved, as shown at U. The forward and rear faces of the vertical portion of the L-shaped piece are recessed, as shown at V and W, respectively, the object of the forward recess being to guide the upper rear portion of

the elastic pad, while the recess in the rear has for its object to accommodate the ends of clip plates or ties, so as to allow my invention to be applied to thill-couplings, where the tie-plates or the clips are of different lengths, and at the same time retaining it in a vertical or nearly vertical position, as shown in the accompanying drawings.

The manner of attaching my invention is as follows: The pivotal bolt D and the thill-iron are removed and the L-shaped piece is inserted between the perforated ears, with its T-head resting upon the upper edges of the same. The elastic pad is then placed in the socket-plate and the thill-iron secured to the ears of the clip, as hereinbefore described. While in this position the concaved upper portion of the elastic pad, fitting around the lower portion of the eye of the thill-iron, forces it against the pivotal bolt, thus preventing rattling, and should the pad become worn through usage the set-screw is screwed upwardly, forcing the said pad against the eye of the thill. Thus it will be seen that the pad may be, by means of the set-screw, kept in contact with the eye of the thill-iron at all times.

From the foregoing description, taken in connection with the accompanying drawings, the operation and advantages of my invention will be readily understood without requiring further explanation. It will be seen that it is simple and strong in construction, inexpensive to manufacture, and is exceedingly useful for the purpose for which it is designed.

Having thus described my invention, I claim and desire to secure by Letters Patent of the United States—

1. In an attachment for thill-couplings, the combination of an L-shaped piece having a screw-threaded aperture in its base, and a T-head with a set-screw, a socket-plate swiveled thereto, said socket-plate formed with inclined ends and upwardly-projecting arms, and an elastic pad the lower forward and rear edges of which are beveled and its top concaved, substantially as and for the purpose herein described.

2. In an attachment for thill-couplings, the combination of an L-shaped piece having a screw-threaded aperture in its base and a recess in its forward face, with a set-screw, a

socket-plate swiveled to one end of said screw, and an elastic pad seated in said socket-plate, and adapted, when vertically adjusted, to be guided in the recess in the forward face of said L-shaped piece, substantially as and for the purpose herein described.

3. The combination of a thill-coupling, substantially as herein described, with an L-shaped piece having a T-head, and a screw-threaded perforation in its base, and having recesses in its forward and rear faces, a set-

screw, a socket-plate swiveled to one end of said screw, and an elastic pad seated in said socket-plate, substantially as and for the purpose herein described. 15

In testimony that I claim the foregoing as my own I have hereunto affixed my signature in presence of two witnesses.

FRANK. P. MUSSER.
